US0D1108798S

(12) **United States Design Patent** (10) **Patent No.:** **US D1,108,798 S**
(45) **Date of Patent:** **** Jan. 13, 2026**

(54) **HANDBAG**

(71) Applicant: **Bottega Veneta S.R.L.**, Montebello Vicentino (IT)

(72) Inventor: **Matthieu Blazy**, Milan (IT)

(73) Assignee: **BOTTEGA VENETA S.R.L.**, Montebello Vicentino (IT)

(**) Term: **15 Years**

(21) Appl. No.: **29/958,532**

(22) Filed: **Aug. 20, 2024**

(51) LOC (15) Cl. **03-01**

(52) U.S. Cl.

USPC **D3/232**

(58) **Field of Classification Search**

USPC D3/232-233, 242-243, 245-246, 318, D3/322

CPC A45C 3/06; A45C 1/00; A45C 1/02; A45C 3/00; A45C 1/024

See application file for complete search history.
